(57) **CLAIM**

The ornamental design for a container, as shown and described.

DESCRIPTION

FIG. 1 is a birds-eye perspective view of my new design for a container formed of a thin sheet of transparent material, with a lid shown in phantom lines which forms no part of the claimed design, exploded away and disposed above the container;

FIG. 2 is a top plan view of the container of FIG. 1, the bottom view of which is substantially the same and therefore not shown;

FIG. 3 is a front side elevational view of the container as viewed in FIG. 1, the opposite side of which is a mirror image and therefore not shown;

FIG. 4 is a left side elevational view of the container as viewed in FIG. 1, the opposite side of which is a mirror image and therefore not shown;

FIG. 5 is a cross-sectional view taken along lines 5—5 in FIG. 2;

FIG. 6 is a cross-sectional view taken along lines 6—6 in FIG. 2; and,

FIG. 7 is a birds-eye perspective view of the second embodiment of my new design, formed of a thin sheet of opaque material, with a lid shown in phantom lines which forms no part of the claimed design, exploded away and disposed above the container.
